COMBINATION GARMENT

Sidney M. Shuster, Philadelphia, Pa.

Application December 7, 1951, Serial No. 260,391

2 Claims. (Cl. 2—126)

1

The subject matter of this invention relates to garments, especially but not exclusively to the "doublet" or two-garment combination type, and achieves the objective of providing a combination garment of the type designated from which the side elements, consisting of sleeves and portions of the body element, may be readily and detachably removed from the body of the garment and as readily reattached, thus creating two distinct, conventional garments out of one.

As stated, my invention can be applied ideally to the "doublet" type of garment currently popular, wherein the sleeves and adjoining sections of the body are made of one material and the remaining portion of the body is made of a different or contrasting material, thus creating the illusion of two separate garments being worn superposed one upon the other, such as a shirt and vest, or shirt and slipover sweater. My invention achieves the creation of two actual garments from one, the removal of the side elements, consisting of sleeves and adjoining portions of the body element, transforming the "doublet" garment into a new, vest-like garment.

However, my invention is not restricted to the aforementioned "doublet" type of garment, but is as readily adaptable to any form or style of garment having sleeves, such as jackets, sweatshirts, ski-suits, special garments for spectators or participants in various sport activities, shirts, playsuits, riding habits, and the like. It can also be adapted to sleeveless garments, where occasional removal of side portions of the body of the garment is advantageous. It can be adapted for knitted, as well as woven garments and, in fact, to every such type of garment in use.

The principal object of my invention, therefore, is the construction of a combination garment, of the types described, provided with removable side elements, the side elements comprising each a sleeve with a section of its adjacent body element, whereby a complete distinctive garment is created by the removal of the side elements, and a complete distinctive garment is created by the reattachment of said side elements.

Another important object of my invention is to provide various motif designs woven or imprinted on the main body portion of the garment and similar or properly contrasting motif designs woven or imprinted upon the detachable side elements, so that two or more different sets of side elements may be provided for each main body element, the attachment of a different set of side elements to the body element presenting

a distinctive and entirely novel, as well as practical, artistic effect. This interchangeable effect is as well adaptable to the use of color combinations and contrasts.

5 5 A third important object of my invention is to devise a construction in which the attaching means will be flat and completely concealed from view when the side elements are secured to the balance of the garment, and also when the side elements are removed, so that a smooth and even surface will be apparent at all times around the points of joinder of the side elements to the main body element.

10 With these and other objects, advantages and 15 functional features in view, my invention consists of the novel features of construction, combination and arrangement of parts as will hereinafter be more fully described, illustrated in the accompanying drawings, wherein:

15 20 Fig. 1 is a front elevation of a garment constructed according to my invention, showing one of the detachable side elements apart from the body of the garment;

Fig. 2 is an enlarged view on the same elevation as Fig. 1, showing the construction and arrangement of the fastening elements on the body of the garment and on the detachable side element;

25 Fig. 3 is an enlarged view similar to a portion of Fig. 1, with a portion of the outer surface broken away to show cooperation of the fastening elements;

30 Fig. 4 is an enlarged cross-sectional view on lines 4—4 of Fig. 3;

Fig. 5 is a view similar to Fig. 2 but showing a 35 modified embodiment together with transposition of the locking and unlocking slide member carried by the fastening elements;

Fig. 6 is an enlarged view similar to Fig. 3 with a portion of the upper surface of the garment broken away and a portion of the front of the garment broken away to disclose inner construction; and

40 Fig. 7 is an enlarged cross-sectional view taken on lines 7—7 of Fig. 6.

45 Similar reference characters designate similar parts throughout the different views.

50 Illustrative of the embodiments thus disclosed, and referring now to the drawings, my invention comprises a garment 1 having a main body element 2 and detachable side elements 3. The main body element 2 has the material at the marginal portions of the side openings 4 folded inwardly and secured in position by two lines of stitching 5 which also pass through a tape 6 which carries a set of fastening elements 7. As shown in

Fig. 1, the fastening elements 7 are positioned inwardly of the edge of the side opening 4, with the tooth ends thereof facing outwardly from the main body element 2. The free ends of the tape 6 are secured in adjacent position to each other at the bottom of the side opening 4 so that a continuous line of fastening elements 7 surrounds said side opening 4 on the inner surface of said marginal portion, the free ends of the tape 6 being slightly apart from each other, however, so as to allow the connection thereto of a complementary line of fastening elements 8 which are secured to the side element 3.

The detachable side elements 3, as shown in Figs. 1 and 2, comprise each a sleeve 9 and a small section 10 of the main body of the garment 1. Each side element 3 has the marginal portion at its body opening folded inwardly and two lines of stitching 11 secure this fold in position and also secure thereto a tape 12 which carries a set of fastening elements 8, on which is mounted a locking and unlocking slide member 13. The tape 12 is secured in such a manner that the fastening elements 8 project outwardly and beyond the edge of the side element 3, with the tooth ends of the fastening elements 8 facing outwardly, and the free ends of the tape 12 are secured in adjacent position to each other at the bottom of the marginal portion of the side element 3, so that proper registry is provided for the two sets of fastening elements 7 and 8 when juxtaposed.

It will be seen from the foregoing that when the side element 3 is attached to the main body element 2, with the fastening elements 7 and 8 properly joined, said fastening elements 7 and 8 will be entirely concealed from view by the overlapping marginal flap 14, and the garment 1 will present a smooth, finished appearance at the point of joinder.

The locking and unlocking slide member 13 is preferably carried by the side element 3, as shown in Fig. 2, but it may be carried instead by the main body element 2, as shown in Fig. 5. Provision may also be made for the slide member 13 to be operative from the inside of the garment 1 or from the outside thereof, although the latter is preferred since removal and attachment of the side elements 3 may thus be made while the garment is being worn.

In Figs. 5, 6 and 7 there is shown a modified form of combination garment, in which an inside flap 15 is provided around the marginal opening of the main body element 2. It has been found to be desirable in some forms of garments to provide a means of protection to the skin of the wearer from the toothed edges of the fastening elements 7 when the garment is worn without the side elements 3, since these fastening elements 7 are apt to injure the skin unless proper protection is afforded. Such protection is accomplished by providing an inside flap 15 which is secured around the marginal edge of the side opening 4 by means of the same lines of stitching 5 which secures the tape 6 to the main body element 2. The flap 15 extends outwardly beyond the fastening elements 7, on the inside of the main body element 2 so as to encase the fastening elements 7 between it and the marginal flap 14, the marginal flap 14 extending outwardly farther so that the inside flap 15 cannot be seen from the outside in either form of the combination garment.

In operation, to secure the side element 3 to the main body element 2 the male element on the

slide member 13 which is attached to one set of fastening elements 7 is inserted into the female element of the slide member 13, which is attached to the other set of fastening elements 8. The slide member 13 is then drawn forwardly its full length of travel around the fastening elements 7 and 8, securing them to each other and attaching the side element 3 to the main body element 2. When the slide member 13 is drawn rearwardly its full length of travel the two sets of fastening elements 7 and 8 are released from one another and the side element 3 is detached from the main body element 2. In either case a complete garment is provided, in the latter case a vest-like garment and in the former a fully sleeved garment.

As shown in Fig. 2 and Fig. 5 the free ends of the tapes 6 and 12 overlap the fastening elements 7 and 8 so as to provide the necessary spacing for the hooking on of the slide member 13.

It is thus apparent that my invention provides a combination garment which can be made into either of two distinct, complete garments by the simple expedient of operating the slide member 13 to attach or detach the side elements 3 from the main body element 2.

Further novelty and utility is provided in connection with the practical and artistic effect of my invention, by providing two or more sets of side elements which can be substituted for one another, each of said sets having a different motif design, either similar to or contrasting to the design of the main body element. In various types of garments, side elements of different color from the main body element can be substituted as desired.

While the embodiment shown and described represents a preferred embodiment of my invention and of the materials suggested for its construction, it is to be distinctly understood that various changes may be made in the steps of construction and in the construction and arrangement of parts thereof without departing from the spirit and scope of my invention, or sacrificing any of the advantages thereof inherent therein, or the features of novelty disclosed.

I claim:

1. A combination garment comprising a main body element, detachable side elements and a slideable fastener adapted to removably attach the side elements to the main body element, each of the side elements comprising a sleeve and an adjacent shoulder section of the garment body completely surrounding the sleeve and integral therewith, the side elements and the main body element provided at each of their attaching edges with a line of cooperating fastener members extending throughout the length of such edges to allow for complete detachment of the side elements from the main body element, the side elements having their fastener members projecting beyond their attaching edges, the main body element having its fastener members inset from its attaching edges a distance greater than the projection of the fastener members of the side elements, whereby the fastener members are concealed from view in interlocked arrangement, and a locking and unlocking slide member cooperating with said fastener members to attach the side elements to the main body element and detach them therefrom as desired.
2. A combination garment comprising a main body element, detachable side elements and a slideable fastener adapted to removably attach

the side elements to the main body element, each of the side elements comprising a sleeve and an adjacent shoulder section of the garment body completely surrounding the sleeve and integral therewith, the side elements and the main body element provided at each of their attaching edges with a line of cooperating fastener members extending throughout the length of such edges to allow for complete detachment of the side elements from the main body element, the side elements having their fastener members projecting beyond their attaching edges, the main body element having its fastener members inset from its attaching edges a distance greater than the projection of the fastener members of the side elements, whereby the fastener members are concealed from view in interlocked arrangement, and a locking and unlocking slide member cooperating with said fastener members to attach the side elements to the main body element and de-

20
6
tach them therefrom as desired, the slide member mounted on the side element fastener and removable as a unit therewith.
